UNITED STATES PATENT OFFICE.

EDWARD H. McCLOUD, OF COLUMBUS, OHIO.

FOLDING DOOR.

No. 924,686.

Specification of Letters Patent.

Patented June 15, 1909.

Application filed March 4, 1908. Serial No. 419,208.

To all whom it may concern:

Be it known that I, EDWARD H. McCLOUD, a citizen of the United States, residing at Columbus, in the county of Franklin and 5 State of Ohio, have invented a certain new and useful Improvement in Folding Doors, of which the following is a specification.

This invention relates more particularly to the class of doors that include sections 10 that are hingedly related to each other and fold vertically together by movement toward the top of the doorway.

The chief object of the invention is to provide a construction whereby the door is more 15 easily and conveniently flexed in folding.

Other objects will appear from the following description.

In the accompanying drawings, in which is illustrated but one embodiment of the invention—Figure 1 is a front elevation looking at what is ordinarily the inner side of the door; Fig. 2 is a horizontal section on the line $y-y$ Fig. 1; Fig. 3 is a vertical section on the line $x-x$ Fig. 1; Fig. 4 is a section 20 like that shown in Fig. 3 except that the door is shown as raised to folded position; Fig. 5 shows in front and partial sectional view a modification of the means for counterbalancing and hoisting the door, there 25 being included in this view an illustration of the door for the purpose of indicating the relation of the modified counterbalancing and hoisting means thereto. In this view parts are broken out for convenience in 30 illustration.

Referring more particularly to Figs. 1 to 4 inclusive, 6 and 7 designate respectively the upper and lower door sections. These sections are hinged together as seen at 8 so 35 as to be capable of being folded toward each other. 9 and 10 are links pivotally secured at their upper ends and in horizontal line with each other to small but strong brackets 11 and 12 suitably secured to the 40 wall above the line of the top of the doorway. The lower ends of the links 9 and 10 are pivotally secured to pins 13 and 14 on the upper part of the lower section 7. The axes 45 of the pivotal connections of links 9 and 10 with the section 7 are shown to be parallel to the axes of the hinges connecting the door sections and to lie in a plane considerably beyond the plane of the face of the door, but said links lie in planes beyond the 50 edges of the door sections so as not to obstruct the movements of the door sections

in folding and unfolding. In their upper portions the links 9 and 10 are made with slots 9^a and 10^a respectively, into which extend pins 15 and 16 projecting laterally 60 from near the upper corners of the upper door section 6. These pins are shown to be on brackets secured to the face of the said section 6. To reduce friction in these connections the pins 15 and 16 can be provided 65 with rollers 15^a and 16^a respectively to run on short tracks 9^b and 10^b projecting from the links parallel to the slots 9^a and 10^a respectively.

The lower corners of the lower door section 70 7 are provided with laterally projecting pins 17 and 18 secured to the section by means of suitable brackets. On these pins 17 and 18 are rollers 19 and 20 that run on suitable tracks 21 and 22 secured vertically at opposite sides of the doorway. Parallel to the tracks 21 and 22 are inwardly-turned flanges 23 and 24 behind which extend hooks 25 and 26 carried on the pins 17 and 18 to prevent the lower portion of the lower section from 80 pulling out.

Attached to the pins 17 and 18 or to the hook members 25 and 26 are hoisting chains 27 and 28 that are shown in Fig. 1 to pass upward and over suitable pulleys 29 and 30 secured above the doorway. As shown at the upper right-hand corner of Fig. 1 the hoisting chains are indicated to be passed over a double pulley, the additional pulley designated 31, and to be connected to a counterbalancing weight, as seen at 32. The shaft of the pulleys 30 and 31 can be provided with a gear-wheel 33 engaged by a pinion 34 operated by a sprocket-wheel 35 and chain 36.

The means for counterbalancing or hoisting the door is susceptible of much modification and does not constitute invention with me except so far as such might form an element in combination with my invention. Another means for counterbalancing and 95 hoisting the door is suggested in Fig. 5. It is essentially a fusee and comprises, as shown, a stationary shaft 37, a drum 38, with springs 39 and 40 connecting the shaft and drum, and spiral pulleys 41 and 42 on which the 100 hoisting chains, connected to the shutter, as before described, run. The spiral form of the pulleys tends to equalize the pull of the springs as they weaken in power by unwinding when the door is raised.

If very light doors be used they can be raised by hand solely, and the mechanical

operating and counterbalancing devices described dispensed with, the door being held in position to which raised by any suitable device that might suggest itself to any ordinary mechanic doing the work. The chief point of my invention is the peculiar means for securing the easy flexing of the door at the joint between the sections. In respect to this it will be observed, referring more particularly to Fig. 3, that the point of supplemental flexion 15 is amply beyond a straight line connecting the point of pull 17 and the point of resistance 13, and that the point of pull is kept in a line well beyond said point of flexion by the flanges 23 and 24 and hooks 25 and 26 holding the lower end of the lower section in its fixed path. In this operation the upper section follows or trails, so to speak, being free to accommodate itself to the movements of the principal hinging point 15 but properly guided by its connection with the slotted portions of the links to take the desired positions when opened or closed.

A step-like lap-joint between the door sections 6 and 7 near where they are hinged together can be used if desired.

When in doorway-closing position the door sections can be locked from operation by means of a stationary member 43 on the lower section and extending across the joint between the sections and engaged by a movable member 44 on the upper section.

What I claim and desire to secure by Letters Patent is:

1. A folding door including, in combination, two sections secured in hinged relation to each other, the upper edge of the upper section being free to move toward and from the building having the opening to be closed, a suspending link hingedly connected with the lower of said sections and with the building having the opening to be closed, and means for guiding the lower end of said lower section, the point of connection of said link with said lower section lying outside of a straight line connecting the guided portion of the lower section and the suspended point of said link and means for controlling the movement of the upper of the hinged sections.

2. A folding door including, in combination, two door sections secured in hinged relation to each other, the upper edge of the upper section being free to move toward and from the building having the opening to be closed, a suspending link hingedly connected with the lower of said sections and with the building having the opening to be closed, and means for guiding the lower end of said lower section, the point of connection of said link with said lower section lying outside of a straight line connecting the guided portion of the lower section and the suspended point of said link, means connecting the upper section slidably with said link.

3. A folding door including, in combination, two door sections secured in hinged relation to each other, the upper edge of the upper section being free to move toward and from the building in which the door is installed, suspending links lying beyond the vertical edges of the upper section, hingedly connected with the upper corners of the lower of said sections and with the building having the opening to be closed, and means for guiding the lower end of said lower section, the points of connection of said links with said lower section lying outside of straight lines connecting the guided portions of the lower section and the suspended points of said links, and means for controlling the movement of said upper section.

4. A folding door including, in combination, two door sections secured in hinged relation to each other, the upper edge of the upper section being free to move toward and from the building in which the door is installed, and said section being provided with pins 15 and 16, suspending links hingedly connected with the lower of said sections and with the building in which the door is installed, and means for guiding the lower end of said lower section, the points of connection of said links with said lower section lying outside of straight lines connecting the guided portions of the lower section and the suspended points of said links, said links provided with slots 9^a and 10^a, in which the aforesaid pins 15 and 16 project for controlling the movement of the upper section.

5. A folding door including, in combination, two door sections secured in hinged relation to each other, the upper edge of the upper section being free to move toward and from the building in which the door is installed, said upper section provided with pins 15 and 16, and rollers 15^a and 16^a, suspending links hingedly connected with the lower of said sections and with the building in which the door is installed, and means for guiding the lower end of said lower section, the points of connection of said links with said lower section lying outside of straight lines connecting the guided portions of the lower section and the suspended points of said links, said links provided with slots 9^a and 10^a and tracks 9^b and 10^b, said pins 15 and 16 projecting into said slots for controlling the movement of the upper section and said rollers running on said tracks.

6. A folding door including, in combination, two door sections secured in hinged relation to each other, a suspending link hingedly connected with the lower of said sections and with the building having the opening to be closed, means for guiding the lower end of said lower section, the point of connection of said link with said lower section lying outside of a straight line connecting the guided portion of the lower section and the suspended

point of said link, the upper section having a sliding connection with said link, and means connected with said lower section for raising and counterbalancing the door.

7. A door composed of two sections arranged one above the other with their adjacent edges hinged together, suspending links for suspending the door adapted to be pivoted at their upper ends to the building having the opening to be closed and pivotally connected with the lower section at points offset from the line of the hinged connection of the sections, said links having guiding connections with the upper door section, and means for guiding the lower portion of the lower door section toward the pivotal connections of the links with the building when the door is raised, whereby the door is flexed by flexing the lower section with reference to the links, substantially as described.

8. In a folding door, the combination of two door sections hinged together, and links hingedly connected to one of said sections at points offset from the hinge of the section, said links having guiding connections with the other section.

9. In a folding door, the combination of two door sections hinged together, and links hingedly connected to one of said sections at points offset from the hinge of said section,

said links having movable connections with the other section.

10. In a folding door, the combination of upper and lower door sections hinged together, suspending links having their upper ends adapted for pivotal connection to a building and their lower ends pivotally connected to the lower door section at a point below the hinges connecting the sections together, a sliding support for the top of the upper section, a guide way, means for engaging the lower section with the guide way when the door is down, and means for counterbalancing the door.

11. In a folding door, the combination of two door sections hinged together, suspending members having their upper ends adapted for pivotal connection to a building, and their lower ends pivotally connected to the door, the disposition of the pivotal points of said arms being such as to impart a reciprocating movement of the upper door section when the lower section is moved, a sliding support for the top of the upper section, a slide way for the lower section, and means for counterbalancing the door.

EDWARD H. McCLOUD.
